UNITED STATES PATENT OFFICE.

FREDERICK WM. HUTTON, OF BROCKTON, MASSACHUSETTS.

DESIGN FOR AN AUTO-MAT.

46,832.

Specification for Design.

Patented Jan. 5, 1915.

Application filed April 13, 1914. Serial No. 831,649. Term of patent 7 years.

To all whom it may concern:

Be it known that I, FREDERICK W. HUTTON, a citizen of the United States, residing at Brockton, in the county of Plymouth and Commonwealth of Massachusetts, have invented a new, original, and ornamental Design for Auto-Mats, of which the following is a specification, reference being had to the accompanying drawing, forming a part thereof.

The figure is a perspective view of an auto mat showing my new design.

I claim:

The ornamental design for an auto mat as shown.

FREDERICK WM. HUTTON.

Witnesses:

OSCAR CALKINS,
CLYDE L. ROGERS.
